UNITED STATES PATENT OFFICE.

FRANK G. HOGLAND, OF ROCKFORD, ILLINOIS.

DESIGN FOR A BASE-PLATE EXTENSION FOR SEWING-MACHINES.

SPECIFICATION forming part of Design No. 31,594, dated October 3, 1899.

Application filed September 5, 1899. Serial No. 729,581. Term of patent 7 years.

To all whom it may concern:

Be it known that I, FRANK G. HOGLAND, a citizen of the United States of America, residing at Rockford, in the county of Winnebago and State of Illinois, have invented and produced a new and original Design for Base-Plate Extensions for Sewing-Machines, of which the following is a specification, reference being had to the accompanying drawings, forming part thereof.

Figure 1 is a top plan view of a base-plate extension, showing my new design. Fig. 2 is a sectional view taken on the line 2 2 of Fig. 1.

As shown in the drawings, the leading or material features of my design consist of the elongated openings A in the extension-plate, disposed as shown in Fig. 1, and the semi-circular lugs B, having openings C therein circular in form below and gradually widen-

ing into an elongated form above, as shown in Fig. 2, the said lugs being depressed below the upper face of said extension-plate in an amount about equal to the thickness of said plate.

Having described my invention, what I claim as new, and desire to secure by Letters Patent, is—

The design for a base-plate extension for sewing-machines, as herein shown and described.

In testimony whereof I have signed my name to this specification in the presence of two subscribing witnesses.

FRANK G. HOGLAND.

Witnesses:

L. L. MORRISON,
R. G. McEVoy.
